UNITED STATES PATENT OFFICE.

ERNST MOHR, OF MILWAUKEE, WISCONSIN, ASSIGNOR TO THE KIECKHEFER BROTHERS COMPANY, OF SAME PLACE.

DESIGN FOR A SPOON.

SPECIFICATION forming part of Design No. 28,789, dated June 7, 1898.

Application filed February 28, 1898. Serial No. 672,103. Term of patent 14 years.

To all whom it may concern:

Be it known that I, ERNST MOHR, of Milwaukee, in the county of Milwaukee and State of Wisconsin, have invented a new and useful Design for Spoons, of which the following is a description, reference being had to the accompanying drawings, which are a part of this specification.

My invention has relation to a design for spoons.

Figure 1 illustrates a plan view of the spoon, and Fig. 2 an edge view thereof.

The leading feature of my design consists of a spoon-bowl A, having extending therefrom a handle B, said handle being formed into a continuous loop, so as to produce an open effect throughout the length of the handle to the point of its attachment to the bowl, with the width of the loop in the same plane as the width of the spoon-bowl. Said handle

is curved upwardly at its outer end, as indicated at C, and curved downwardly at its inner portion to its inner extremity, where it connects with the rear end of the bowl, as indicated at D. The side members of the inner portion of the handle run on parallel lines, while the side members of the remaining length of the loop outwardly are in divergent lines.

Having thus described my invention, what I claim as new, and desire to secure by Letters Patent, is—

The design for a spoon substantially as herein shown and described.

In testimony whereof I affix my signature in presence of two witnesses.

ERNST MOHR.
